DIAL KNITTING MACHINE AND METHOD

Herman E. Crawford, Kernersville, N. C.

Application July 8, 1954, Serial No. 442,147

12 Claims. (Cl. 66—24)

This invention relates to a knitting machine of the type which knits both a ribbed and a plain fabric and, more especially, to an improvement in such a knitting machine for enabling continuous knitting of a fabric, such as an article of hosiery, from top to toe and including a ribbed top, some of the stitches of which are knit with dial needles and others of which stitches are knit with cylinder needles and a body portion or leg portion knit from cylinder needles only to form a plain fabric.

It is an object of this invention to provide an improved knitting machine for continuously knitting an article of hosiery, comprising a ribbed top, knit on dial and cylinder needles and automatically transferring the dial stitches from the dial needles to cylinder needles, which operation will eliminate the use of a ribbing machine and hand transferring the top to a plain or cylinder needle knitting machine.

It is another object of this invention to provide improved means for maintaining the fabric under sufficient tension as it is being knitted by the machine to obviate the necessity of take-up rolls or weights to shed stitches from the dial needles as has heretofore been the case. As is well known to those familiar with the art, when a take-up is used to maintain the knitted fabric under tension as it is shed from the dial needles, the hosiery or other article being knitted must, of necessity, be knitted in a continuous operation and wherein successive articles are connected by a row of stitches which subsequently have to be cut and pulled out by the knitting machine operator to separate the articles. This has been an expensive and time consuming operation and is no longer required with the present machine, since each sock or other article is knitted separately and dropped out of the machine as it is completed.

It is another object of this invention to provide improved method and means for transferring stitches from dial latch needles to cylinder latch needles including improved dial transfer cams for moving dial needles outward to an intermediate position with dial latch intercepting means to hold the dial needle latches partially open when thus opened by the stitches thereon. Pattern-jack-controlled needles are then raised through the dial stitches held open by the latches. Thereafter the latches are released from the intercepting means, the dial needles are moved to fully outward position and then withdrawn from the stitches to complete the transfer operation.

It is another object of this invention to provide an improved pattern controlled dial latch opener which opens the latches on the dial needles after the transfer operation and after dial stitches are formed.

It is still another object of this invention to provide co-axial cylinder needle and selector or pattern jack cylinders with means to raise and lower the needle cylinder along with the sinker head independently of the jack cylinder to vary the lengths of stitches formed on the cylinder needles. This permits the use of relatively large jack cylinder and relatively long selector jacks, thereby providing for a wider range of patterning than has heretofore been possible without subjecting the controls for the raising and lowering of the needle cylinder to excessive stresses.

Some of the objects of the invention having been stated, other objects will appear as the description proceeds,

2

when taken in connection with the accompanying drawings, in which—

Figure 1 is a front elevation of the upper portion of the improved knitting machine;

5 Figure 2 is an enlarged elevation of the upper left-hand portion of Figure 1;

Figure 3 is a left-hand side elevation of the knitting machine looking at the left-hand side of Figure 1;

10 Figure 4 is an enlarged elevation of the upper right-hand portion of Figure 3;

Figure 5 is an enlarged sectional plan view taken substantially along line 5—5 in Figure 1;

Figure 6 is an enlarged sectional plan view taken substantially along line 6—6 in Figure 2;

15 Figure 7 is a sectional plan view taken substantially along line 7—7 in Figure 2;

Figure 8 is a fragmentary plan view of the upper right-hand portion of Figure 7 showing the parts in a different position;

20 Figure 9 is an enlarged sectional plan view taken substantially along line 9—9 in Figure 2;

Figure 10 is an enlarged vertical sectional view, through the needle cylinder, dial and sinker head, taken substantially along line 10—10 in Figure 4;

25 Figure 11 is a fragmentary vertical sectional view through a portion of the dial and latch ring taken substantially along line 11—11 in Figure 9;

Figure 12 is a sectional plan view through a portion of the dial taken substantially along line 12—12 in Figure 11;

30 Figure 13 is a rear elevation of the upper portion of the knitting machine taken substantially along line 13—13 in Figure 4;

Figure 14 is an enlarged vertical sectional view taken substantially along line 14—14 in Figure 13;

35 Figure 15 is a fragmentary vertical sectional view through the needle cylinder and the selector jack cylinder and showing the novel manner in which the needle cylinder is supported;

40 Figure 16 is a schematic view of the selector jacks showing the pattern arrangement of the butts thereon as shaded areas;

Figures 17 through 26 are vertical sectional views through the main pattern drum shown in Figures 3 and 45 5, said sections being taken progressively from left to right in Figure 5 and showing the various cams thereon and the levers and thrust rods operated thereby;

45 Figure 27 is a plan view of the cams in the dial as if looking down thereon substantially along line 27—27 in Figure 10 and omitting the dial cap to which these cams are attached;

50 Figure 28 is a fragmentary view of the lower left hand portion of Figure 27 with the dial cams and dial needles shown in different positions;

55 Figure 29 is a view similar to Figure 27 showing some of the dial cams and dial needles in different positions;

Figure 30 is a fragmentary vertical sectional view through the dial and cap taken substantially along line 30—30 in Figure 27 and showing the latch opener opening a latch on one of the dial latch needles;

60 Figure 31 is a fragmentary vertical sectional view through the dial taken substantially along line 31—31 in Figure 27;

Figure 32 is a fragmentary vertical sectional view through the dial taken substantially along line 32—32 in Figure 27;

65 Figure 33 is a fragmentary vertical sectional view through the dial taken substantially along line 33—33 in Figure 28;

70 Figure 34 is an enlarged sectional plan view taken substantially along line 34—34 in Figure 1 and showing only the top lever and the cam which operates this lever;

Figure 35 is a view similar to Figure 34 except showing the next lever, and cam for operating the same, below the lever and cam shown in Figure 34;

Figure 36 is a view similar to Figure 35 except showing the next lever, and cam for operating the same, below the lever and cam shown in Figure 35;

Figure 37 is a developed view of the cams surrounding the needle cylinder and showing the path of travel of some of the butts of the jacks and the needles and the hooks thereof;

Figure 38 is a fragmentary rear elevation looking substantially along line 38—38 in Figure 3.

Referring more specifically to the drawings, it will be observed in Figures 1 and 3 that the lower portion of the knitting machine is similar to a Scott & Williams Model B-5 machine, and substantially as disclosed in the patent to R. W. Scott, No. 1,152,850, in that the means for rotating and reciprocating the needle cylinder, the main pattern drum and its driving connections, the primary pattern chain and the means for driving the dial are conventional and, therefore, only a brief description thereof will be given.

Referring to Figures 1 and 3 it will be observed that the machine comprises legs 10 supporting the base plate 11, an intermediate or jack cam plate 12 and a drum supporting plate 13 supported by a rectangular frame 14. The intermediate cam plate 12 is supported at one side on the frame 14 and its opposite side is supported on a vertically disposed frame member 15 whose lower end is fixed to one edge of the base plate 11. A bevel gear 16 (Figure 15) is mounted for rotation in the intermediate cam plate 12 and is engaged by the teeth of a bevel gear 17 (Figures 1 and 3) fixed on the left-hand end of a main drive shaft 18 journaled in the frame 14.

The bevel gear 17 is continuously driven in one direction when a clutch collar 20 is moved to the right or to the position shown in Figure 1 and the gear 17 is driven in a reciprocatory manner when the clutch collar 20 is moved to the left in Figure 1 by a pattern wheel 21 through conventional linkage. The main drive shaft 18 is driven by a belt 22 engaging either of a pair of pulleys 23 or 24 and which in Figure 1, is shown in engagement with an idler pulley 25. The pattern wheel 21 is rotatably mounted on a pattern cam shaft 26 driven by a rack wheel 27 fixed thereon which is advanced by a conventional crank arm pivotally mounted on the conventional sector gear which is engaged and driven by the reciprocable driving gear on the main drive shaft 18, in the usual manner.

A rack wheel 30 is fixed on the cam shaft 26, to which step-by-step rotation is imparted by conventional means, not shown, controlled by a conventional pattern chain 31. The manner in which step-by-step rotation is imparted to the rack wheel 30 from the pattern chain 31 is clearly shown and described in said Patent No. 1,152,850 and, since this is conventional, a further description thereof is deemed unnecessary. It might be stated that, in the present instance, the right-hand edge of the pattern chain 31 in Figure 1, is provided with suitable cams or lugs for controlling step-by-step rotation of the rack wheel 30 and the left-hand edge thereof is provided with a plurality of lugs for controlling step-by-step rotation of an auxiliary pattern drum 33 rotatably mounted on the left-hand end of the shaft 26 in Figure 1. The driving means for the auxiliary pattern drum will be later described.

It is thus seen that the pattern chain 31 will be moved in a step-by-step manner by the rack wheel 30 in a conventional manner to, in turn, position the pattern wheel 21 and the clutch 20 so the bevel gear 16 in the cam plate 12 will be driven either continuously in one direction or will be reciprocated, depending upon the position of the clutch collar 20 on the main drive shaft 18.

When the clutch collar 20 is moved into the position shown in Figure 1, or to the right on the main drive

shaft 18, rotary motion is transmitted to the main drive shaft and, when the clutch 20 is moved to the left in Figure 1, reciprocatory motion will be transmitted to the main drive shaft to impart like motion to the bevel gear 17 and the bevel gear 16 in the cam plate 12.

The means for mounting and driving the auxiliary pattern drum 33 in the present application is identical to the manner in which the cam drum 97 in my co-pending application, Serial No. 192,935, filed October 30, 1951, is mounted and driven and, therefore, only a brief description of the same will be given. The auxiliary pattern drum 33 is provided with a rack wheel 50 (Figure 3) which is rotatably mounted on the left-hand end of the shaft 26 in Figure 1 and, in order to prevent free rotation of the rack wheel 50 on the shaft 26, there is provided a suitable friction means in the form of a leaf spring member 51. The upper end of the leaf spring member 51 frictionally engages the rack wheel 50 and its lower end is suitably secured to a bearing bracket 52, the lower end of which is suitably secured to the lower base plate 11 (Figures 1 and 3).

A ratchet pawl 53, pivotally mounted adjacent the upper end of a pawl carrying arm 54, is resiliently urged into engagement with the rack wheel 50. The upper end of the pawl carrying arm 54 has a hooked portion integral therewith which normally engages a latch 55 in the form of a bell crank which has an upwardly extending arm integral therewith.

The latch 55 is oscillatably mounted on an angle clip 56 (Figure 1). The upwardly extending leg of the latch 55 has a detent lever 57 oscillatably mounted thereon, which is normally resiliently urged into engagement with a stud 60 on a stud arm 61 integral with a hub member 62 (Figure 1). The hub member 62 is oscillatably mounted on a shifter shaft 63 fixedly mounted in the frame 14.

The opposite end of the hub 62 has an arm 64 integral therewith which extends forwardly in Figure 1 and to the right and then forwardly again and has mounted therein a stud 65 whose free end is adapted to engage and ride on the left-hand edge of the pattern chain 31. The stud 65 is urged into engagement with the pattern chain 31 by a tension spring 66.

The lower end of the pawl carrying arm 54 is fixed on one end of a shaft 70 journaled intermediate its ends in the upper end of the bearing bracket 52. One end of the shaft 70 has a bunter 71 fixed thereto which is, at times, adapted to be engaged by a quadrant gear, not shown, which is conventional and is clearly shown in said co-pending application Serial Number 192,935. The quadrant gear is also clearly shown and referred to at 75 in Figure 5 of said Patent No. 1,152,850.

It is thus seen that, the auxiliary pattern drum 33 may be moved in a step-by-step manner, as desired, by placing lugs on the left-hand side of the links of the pattern chain 31 so they will engage and raise the stud 65 to thus raise the stud 60 and move lever 55 out of engagement with the hooked portion on the upper end of the pawl-carrying arm 54 to thus allow the ratchet pawl 53 to move rearwardly to engage another tooth on the rack wheel 50. As the quadrant gear, not shown, comes down to engage the bunter 71, the pawl carrying arm 54 will be urged in a counterclockwise direction, in Figure 3, to move the rack wheel 50 and the auxiliary pattern drum 33 a step in rotation in a counterclockwise direction.

The machine also has a conventional train of gears 75 (Figure 1) 76 (Figure 3) and 77, the gear 75 being fixed on the shaft 26 and the gear 77 being fixed to a main pattern drum 80. The pattern drum 80 is rotatably mounted intermediate the ends of a shaft 81, the inner end of which is fixed to the frame 14 and the outer end of which is fixed in the frame 15. The main pattern drum 80 is rotated in a step-by-step manner, by the rack wheel 27, and makes one complete revolution each 75 time a sock or other article is knit.

The circular intermediate cam plate 12 has a reduced portion 35 (Figures 1 and 15) integral therewith in which the upper end of a conventional sock horn 86 has vertical sliding movement. The lower portion of the sock horn 86 is mounted for vertical sliding movement in a plate member 87 suitably secured to the upper surface of the base 11. The sock horn 86 is raised and lowered in a conventional manner, for effecting the desired amount of tension, or length of stitches, in the fabric being knitted. Vertical movement of the sock horn 86 is effected by a crank arm 90 (Figure 3), having conventional adjustment screws therein which are adapted to bear against circularly arranged cam members fixed on the main pattern drum 80.

The crank arm 90 is oscillatably mounted on a shaft 91 (Figure 3) whose right-hand end in Figure 1 is embedded in the vertically disposed frame 14 and whose left-hand end is supported by the frame 15.

The rearwardly extending portion of the drum supporting plate 13 (Figure 3) has a cast yarn cone rack 95 fixed thereon. The yarn cone rack 95 supports a plurality of the usual type of cones 96 onto which yarn Y is wound. The yarn Y which extends upwardly and through a guide 97 is fixed on an arm 100 supported on the upper end of a yarn tension support post 101. The yarn Y passes from the guide 97 downwardly and through a suitable yarn tension and take-up device 105 mounted on a support bracket 106 which is fixed on the yarn tension support post 101. The yarn tension and take-up device 105 may be of the type shown and described in said co-pending application Serial No. 192,935. The yarn Y then passes from the outer end of the yarn tension and take-up device 105 to a novel form of yarn feeding finger (Figures 13 and 14) and will be later described.

All of the mechanism heretofore described is conventional with the exception of the auxiliary pattern drum 33 and means for rotating the same in a step-by-step manner which is shown and described in my said co-pending application Serial No. 192,935.

Referring to Figures 1 through 5 and 15, it will be observed that there is provided a relatively long jack cylinder 115 having slots therein for reception of vertically slidable selector jacks 116 which have a plurality of buits thereon, to be later described.

The jack cylinder 115 is fixed on the bevel gear 16, as by screws 120 (Figure 15). The gear 16, in the intermediate cam plate 12, is held in rotatable position therein by a stationary annular cam plate 121 (Figures 15 and 37) which supports the usual stationary jack cams shown in Figure 37. The top of the sock horn 86 is provided with a hardened steel ring 123 (Figure 15) on which the lower ends of a plurality of hardened steel pins 124 rest. The pins 124 extend upwardly and through vertical holes in a needle cylinder guiding sleeve 125 (Figures 10 and 15) secured to the upper end of the jack cylinder 115, as by screws 126, and in which a plurality of vertical slots 127 are cut in alignment with the respective pins 124.

A ring 130 is fixed to the lower end of a relatively short needle cylinder 131 as by screws 132, and has a plurality of inwardly extending lugs 133 extending into the respective slots 127 in the sleeve 125. The lower surface of each of these lugs 133 is engaged by one of the pins 124. The lower ends of the pins 124 slide against the hardened steel ring 123 above the sock horn 86 as rotation is imparted to the sleeve 125 by the jack cylinder 115.

It is thus seen that, as the sock horn 86 is raised by the crank arm 90, as heretofore described, the pins 124 are raised along with the ring 130 and the needle cylinder 131, thus raising the needle cylinder and the sinker cap, to the later described, without the necessity of lifting the combined weight of the jack cylinder 115 and the needle cylinder 131 as would be the case if the needle cylinder 131 and jack cylinder 115 were made in

one piece. This is one of the important novel features of this machine and allows the tension in and length of the stitches to be varied with a minimum of stress on the part of the crank arm 90 (Figure 3) and associated parts. The long jack cylinder 115 permits a wide range of patterning which could not be attained if the needle cylinder and jack cylinder were of one piece construction.

The needle cylinder 131 is provided with the usual grooves in which a plurality of cylinder needles N are held by a plurality of springs 135 (Figure 10). An upper or cylinder needle cam plate 136 surrounds the needle 131 adjacent its lower end and is supported by a pair of diametrically opposed pillars or posts 137 and 138 (Figure 1) whose lower ends are fixed on the intermediate or jack cam plate 12.

Sinker head and sinker control

A sinker head 140 is conventionally attached to the upper end of the needle cylinder 131 and has a sinker cap 141 mounted thereon in the usual manner to permit rotation of the head 140 and cylinder 131 relative to the cap 141. Of course, the sinker cap 141 holds and guides a plurality of sinkers 142, which are of the plain or smooth-nose type (Figures 10, 14 and 15). The sinkers 142 are guided in their radial movement in radially extending slots in the sinker head 140 by the usual groove or trackway 143 in the sinker cap 141. Means are provided, in Figures 7 and 8, for withdrawing the sinkers at the point at which the yarn Y is fed to the needles, substantially as shown in Patent No. 1,152,850, during rotary knitting and a special sinker pull back cam, to be later described, is provided for moving the sinkers outwardly during reciprocatory knitting such as is done in the heel and toe of circularly knit hosiery.

The sinker cap 141 is caused to oscillate in a well known manner upon changes in direction of rotation of the needle cylinder during reciprocatory knitting and is provided with the usual projections or lugs 145 and 146 (Figures 2 and 7) in which adjustment screws 150 and 151 are mounted to limit the amount of oscillation of the sinker cap upon engagement thereof with opposed sides of a post 152. The lower end of the post 152 (Figures 2 and 4) is fixed to the upper cap plate 136 and also supports a widening pick to be later described.

The sinker cap 141 has a radial groove therein (Figures 7 and 8) in which a stem portion 154 of a sinker drawback or withdrawing cam 155 has radial sliding movement and is held in the sinker cap 141 by a strap member 156 which bridges the slot in the sinker cap 141 and is suitably secured to the sinker cap 141. The outer end of the stem 154 is provided with a fixed operating arm 157 whose free end has a hook 160 thereon. The sinker draw-back cam 155 and the stem 154 are normally urged inwardly by a tension spring 161 (Figures 7 and 8). Inward movement of the sinker draw-back cam 155 is limited by an adjustable stop in the form of an eccentric washer 162 adjustably secured to the stem portion 154 and adapted to engage the strap member 156.

The operating arm 157 is engaged by the upper leg of a bell crank 163 pivotally connected, as at 164 (Figures 6 and 38), to an angle clip 165 fixed on the upper cam plate 136. The other leg of the bell crank 163 is pivotally connected to one end of a connecting link 167 whose lower end is connected to one end of a lever arm 170 pivoted intermediate its ends, as at 171, to a block 172 suitably secured to the lower surface of the upper cam plate 136. The opposite end of the lever 170 has the upper end of a thrust rod 173 pivotally connected thereto, as at 174 (Figures 4 and 6).

The thrust rod 173 extends downwardly and through upper and lower respective thrust rod guides 175 and 176 (Figures 4, 5, 21 and 38), the upper thrust rod guide 175 being suitably secured to the lower surface of the lower cam plate 12 and the lower guide 176 being

suitably secured to the medial portion of the shaft 91 (Figure 3).

The lower end of the thrust rod 173 at times engages the main pattern drum 80 and at other times engages a segmental cam 177 fixed thereon. When the lower end of the thrust rod 173 is in engagement with the pattern drum 80, the sinker draw-back cam 155 occupies substantially the position shown in Figure 7 and, upon the cam 177 (Figure 21) engaging the lower end of the thrust rod 173, through intervening connections, the bell crank 163 is moved to cause the sinker draw-back cam 155 to move outwardly to substantially the position shown in Figure 8. As indicated by the length and position of the cam 177 on the pattern drum 80 (Figure 21) this sinker draw-back cam 155 will remain in its outermost position (Figure 8) during the knitting of all of the knitted article except the heel, toe and foot portions thereof.

The sinker cap 141 is held down along with the needle cylinder 131 by a sinker cap hold-down adjustment nut or screw 189 (Figures 1, 2, 4 and 13) engaging the upper surface thereof and being threadably embedded in a horizontally extending rod 181 whose outer end is adjustably secured in the upper end of a sinker cap hold-down arm 182 which extends downwardly in Figures 2 and 4 and is suitably secured to the sock horn 86 as at 183 (Figure 3). The sinker cap 141 and the sock horn 86 are thereby held in fixed relationship by the hold-down arm 182 to prevent any excessive end-wise play of the hardened pins 124 between the ring 123 and the projections 133 or the ring 130 (Figures 10 and 15).

Selector jack cylinder and pattern means therefor

In the present disclosure there are shown sixty selector jacks 116, one under each cylinder needle N, but it is to be understood that any desired number of selector jacks and corresponding cylinder needles could be arranged around the respective jack cylinder and needle cylinder by merely changing the number of slots or grooves therein. In the preferred embodiment of the invention, a one-by-two rib top hose will be described, that is, two stitches will be formed by adjacent cylinder needles and one stitch formed from a dial needle to form a rib in the top of a sock.

Referring to Figures 15 and 37, it will be observed that the stationary cam plate 121 supports a circular ring or cam 190 having a selector jack gate plate 191 therein. The stationary cam plate 121 also has fixed thereto a stationary jack lifting cam support base 192 (Figure 37) the upper end of which is inverted V-shaped and has a jack lifting or advancing cam or cam plate 193 fixed thereon, the inner end of which extends inwardly towards the selector jack cylinder 115 a greater distance than the base 192 and terminates in close proximity to the selector jack cylinder 115. The lower ends of the jack advancing cam 193 terminate above the normal path of travel of a series of lower or master butts 194, there being one master butt 194 on each of the selector jacks 116 as indicated by the shaded areas in Figure 16. If the butts 194 are allowed to move in their normal path of travel indicated by a broken line 195 in Figure 37, they pass beneath the cam plate 193 and are not raised. However, if the selector jacks 116 are raised slightly so that the lower or master butts 194 engage the cam plate 193, then they ride up the same to elevate the corresponding selector jacks 116 when desired.

Referring to Figure 37 there will be observed two spaced selector jack leveling cams 196 and 197 which engage leveling butts, indicated at 198 and by dark areas in Figure 16, to thus lower all of the selector jacks 116 so the master butts 194 thereof are in close proximity to the upper surface of the cam 190 on the stationary cam plate 121. Each selector jack leveling cam 196 and 197 has a suitable outwardly extending flange which is fixed to the lower surface of the upper cam plate 136 (Figures 2 and 4).

A group of inclined selector fingers 290 through 293 are indicated in Figure 37 to select some of the selector jacks 116 to be raised by the advancing cam 193 to cause selected needles N to take the yarn Y from the yarn feeding station during the knitting of the rib top. It will be observed in Figure 16 that the jacks 116 are provided with four rows of upper pattern butts a, b, c, d which are adapted to engage the respective selector fingers 200, 201, 202, 203, spaced pairs of adjacent jacks having butts a, b, c, d thereon with a single intervening jack between adjacent spaced pairs being devoid of an upper pattern butt. However, the intervening jacks are each provided with a lower pattern butt e or f, also arranged in two staggered rows as shown in Figure 16 which are adapted to engage a second group of selector fingers to be later described (Figure 37). The upper pattern butts a, b, c, d are instrumental in determining which cylinder needles N take yarn Y and the lower pattern butts are instrumental in transferring stitches from dial needles D to cylinder needles N.

The selector fingers 200 through 203 are pivotally mounted in spaced relationship on a post 204 (Figures 1, 2 and 5) whose lower end is fixed in the lower cam plate 12 and whose upper end is fixed in the upper cam plate 136. The selector fingers 200 through 203 are operated by and pivotally connected to corresponding ends of control links 205 through 208 (Figures 2, 5, 34, 35 and 36) whose other ends are adjustably secured in the outer ends of cam levers 210 through 213 pivotally mounted on a post 214 (Figures 1, 5, 34, and 35 and 36). The lower end of post 214 is fixed in the drum supporting plate 13. The cam levers 210 through 213 are spaced from each other in horizontal alignment with respective cams on a selector jack cam drum 217 by suitable collars and washers.

The cam levers 210 through 213 are each urged into engagement with the selector jack cam drum 217 by a tension spring 218, one end of which is secured to each of the levers 210 through 213 and the other end of which is fixed to the upper cam plate support 137 (Figure 5). The selector jack cam drum 217 is rotatably mounted on a post 220 whose lower end is fixed in the drum supporting plate 13. The drum 217 is prevented from free movement by the use of a friction means 221 which may be identical to the friction means shown in my co-pending application Serial No. 192,935 and, therefore, a further description thereof is deemed unnecessary.

The selector jack cam drum 217 is driven through the medium of a ratchet wheel 224 (Figure 1) suitably secured to the lower surface of the cam drum 217. Intermittent step-by-step rotation is transmitted to the ratchet wheel 224 and to the cam drum 217, by a spring-pressed ratchet pawl 225 oscillatably mounted, as at 226 (Figure 5) on an arm of a crank lever 227. The crank lever 227 is oscillatably mounted intermediate its ends, as at 230, on the drum supporting plate 13. One end of a tension spring 231 is connected to the free end of the ratchet pawl 225 and the other end thereof is connected to the crank lever 227 to normally urge the ratchet pawl 225 into engagement with the teeth in the ratchet wheel 224.

The free end of the crank lever 227 (Figure 5) has a cam follower 232 which is normally urged, as by a spring 228, against the side edges of a plurality of irregularly shaped cam members 234, successively, there being four such cam members arranged around a stepping cylinder 235. Suitably secured, as by screws 237, to the upper surface of the drum supporting plate 13 is a bearing bracket 236. The cam drum stepping cylinder 235 is journaled on a shaft fixed in the bearing bracket 236 and the cam stepping cylinder has a gear 241 integral therewith which is one of a chain of gears, not shown, but clearly shown and described in my co-pending application Serial No. 192,935, and which is driven through the pulley 23.

Step-by-step rotation of the cylinder jack cam drum 217 may be momentarily stopped, or stopped for a predetermined period of time, by means of a pivoted lever 242 whose outer or right-hand end in Figure 5 is notched to engage a notch 243 in the crank arm 227 to prevent the cam follower 232 from moving to the left in Figure 5 and to thereby render the ratchet pawl 225 inoperative, substantially as shown in said co-pending application. The lever 242 is pivoted intermediate its ends, as at 245, on the bearing bracket 236 and its inner end is, at times, engaged and urged downwardly by a pin 246 fixed in the outer or right-hand end of a lever 247 pivoted, as at 250, on an angle clip 251 fixed on the drum supporting plate 13 (Figure 5). The opposite end of the lever 247 is engaged by a clip 252 fixed to the upper end of a thrust 253. The thrust rod 253 extends downwardly through the guide bars 175, 176 and, at times, engages the main pattern drum 80 (Figure 26) while, at other times, it engages a segmental cam 254 or 255 fixed on the main pattern drum 80.

It is thus seen that, as either of the cams 254 or 255 moves under and raises the thrust rod 253 in Figure 26, the right-hand end of the lever 247 in Figure 5 is lowered away from the observer to thus raise the right-hand end of the lever 242 and release the cam follower 232 so the tension spring 235 may move the cam follower and the crank arm 227 in a counterclockwise direction and allow the ratchet pawl 225 to move backwardly one tooth on the ratchet wheel 224. Upon engagement of the cam follower 232 with the inclined surface of the next succeeding irregularly-shaped cam 234, the crank arm 227 is rotated clockwise to move the ratchet wheel 224 and the jack selector cam drum 217 a step in rotation in a counterclockwise direction.

Upon the thrust rod 253 being moved off either the cam 254 or 255, through intervening connections, the right-hand end of the lever 242 is moved downwardly by a weight lever 256 (Figure 5) which passes through the right-hand end of lever 242. The opposite end of weight lever 256 is fixed on one end of a rod 257 opposite ends of which are pivotally mounted in respective brackets 260, 261 fixed to the drum supporting plate 13 (Figures 1 and 5). It is thus seen that the weight lever 256 causes the right-hand end of lever 242 to move downwardly into the notch 243, or to the position shown in Figure 5, upon the cam follower 232 reaching the high part of one of the next succeeding irregularly-shaped cams 234.

By referring to Figures 2, 5, and 37 it will be observed that a radially movable selector jack elevating switch cam 260 is slidably mounted in a cam block 261 fixed on the lower cam plate 12. The cam block 261 has a bore therein in which a compression spring 262 is mounted (Figure 5) and whose outer end bears against an abutment 263 fixed to the outer end of the slidable cam 260. The cam block 261 is also provided with a stop screw 264 which limits outward movement of cam 260 when the abutment 263 engages the head of the screw 264. Inward movement of the cam 260 is limited by a stop screw 265 threadably mounted in the abutment 263.

Inward movement of the cam 260 is effected by an adjustable abutment 266 threadably mounted in one end of a lever arm 270 (Figures 2, 4 and 5) which extends downwardly in Figure 2 and then inwardly and is oscillatably mounted on a vertical shaft 271 depending from the lower cam plate 12. The inner end of lever 270 has one end of a connecting rod 272 universally connected thereto (Figures 2 and 4) and other end of which is connected to the upper end of a crank arm 275, as at 276. The crank arm 275 extends downwardly (Figures 3, 4, and 17) and is oscillatably mounted on the shaft 91 intermediate its ends. The lower end of crank arm 275, at times, engages the main pattern drum 80 and, at other times, is adapted to engage a segmental cam 277 fixed on the main pattern drum 80.

It is thus seen that, as the segmental cam 277 moves into contact with the lower end of crank arm 275, the lever 270 is moved in a counterclockwise direction, in Figure 5, to thus move the inner end of the jack operating switch cam 260 inwardly against the jack cylinder 115 and, upon selection of any of the selector jacks 116, in a manner to be later described, the master butt 194 thereof will ride up the inclined surface of the cam 260.

The selector jacks 116 may be selected to ride up the surface of the inclined cam 260 by a pair of selector fingers 280, 281 (Figures 2, 4, 5 and 37) which then engage the corresponding lower pattern butts *e, f*.

The fingers 280, 281 are oscillatably mounted on a post 282 and spaced from each other by suitable collars and washers. Links or connecting rods 284, 285 are pivotally connected to the selector fingers 280, 281 and extend to the right in Figure 5 and are resiliently connected to corresponding ends of cam levers 290, 291 (Figures 1 and 5) oscillatably mounted on a post 292. The lower end of post 292 is fixed in the drum supporting plate 13 and the levers 290, 291 are spaced from each other, on the post 292, by suitable collars and washers.

The free ends of the levers 290, 291, at times, engage the periphery of the selector jack cam drum 217 and, at other times, engage respective segmental cams 293, 294 (Figures 1 and 5) fixed to the selector jack cam drum 217. The cam levers 290, 291 are urged in a counterclockwise direction in Figure 5 by a pair of tension springs 295, one end of each which is connected to the levers 290, 291 and the other ends of which are connected to a spring anchor 296 (Figure 5) fixed in the drum supporting plate 13.

It is thus seen that, as either of the levers 290 or 291 is urged into engagement with the periphery of the cam drum 217 by the tension spring 290, the respective selector finger 280 or 281 is rotated slightly in a counterclockwise direction to move its inner end or inclined surface into engagement with the periphery of the selector jack cylinder 115 to engage and raise selector jacks 116 by engaging the lower pattern butts *e* or *f*, as the case may be (Figure 16). This raising of the selector jacks by the selector fingers 280, 281 causes the master butts 194 of the selector jacks 116 to engage the inclined jack raising cam 260 of thus further raise the corresponding selector jacks 116 and associated needles.

It should be noted that the selector fingers 280, 281 and the selector jack raising cam 260 are utilized during the transfer operation, that is, when the stitches which have been formed on the dial needles are transferred to the cylinder needles to be knit thereby after the ribbed top has been knit.

Cylinder needle raising and lowering cams and operating means therefor

Referring to Figure 37, it will be observed that the cams supported on the cam plate 136 include the usual stationary top center cam 300, lower center cam 301, right-hand stitch cam 302 and left-hand stitch cam 303, as well as a pair of right-hand and left-hand needle leveling cams 304, 305, respectively, all of which are secured to a cam block 306 (Figure 6) in back of the needle cylinder 131. The cam block 306 is fixed to the upper bed plate 136. Also, it will be observed in Figures 6 and 37 that the usual narrowing picks 310, 311 are employed and they are interconnected by an adjustable link 312 (Figure 6). The narrowing picks 310, 311 are used during the usual narrowing operations in the heel and toe and will pick up and raise to inoperative position one needle as the needle cylinder revolves in each direction, as usual. The usual widening pick 316 (Figures 4, 6, and 37) is also used for increasing the number of needles in action during the heel and toe after they have been decreased by the narrowing picks. The widening pick 316 shown in the drawing is conventional and only a brief description thereof will be given.

The widening pick 316 (Figure 6) extends outwardly from the needle cylinder 131 and is universally mounted in a shaft 317 oscillatably mounted in the post 152. The right-hand end of the shaft 317 in Figures 2 and 6 is enlarged and has a control wire 320 extending therefrom which is, at times, adapted to be engaged by an extension 321 on the upper end of an operating bar 322, the upper portion of which is guided in a guide plate 323 fixed to the upper cam plate 136 (Figures 4 and 6).

The bar 322 extends downwardly in Figures 1 and 3 and is pivotally connected, as at 324, to a lever arm 325 (Figure 3) the inner end of which engages cams, not shown, mounted on the auxiliary pattern drum 33 for operating the widening pick at the correct time during widening at the heel and toe in a conventional manner.

There is also provided the usual stationary needle guide cams 330, 331 and 332 (Figure 37) which are secured to the upper cam plate 136. The only difference between the cams 330 and 331 and the conventional cams they replace is that the usual inclined portions thereof adjacent the right-hand and left-hand stitch cams 302 and 303 are cut away to accommodate radially movable needle advancing cams 335, 336 (Figure 37). The needle raising or advancing cams 335, 336 (Figure 6) are held out of engagement with the needle cylinder 131 during the knitting of the ribbed top and are provided with stem portions which are pivotal on respective posts 340, 341 the lower ends of which are fixedly secured in the upper cam plate 136. The cams 335, 336 are urged away from the needle cylinder 131 by respective tension springs 342, 343 (Figure 6).

The needle advancing cam 335 is engaged by one end of a lever arm 345 oscillatably mounted intermediate its ends on a post 346 whose lower end is fixed in the cam plate 136. The rear end of the lever arm 345 is engaged by a bunter in the form of an adjustment screw 350 which threadably penetrates one leg of a bell crank 351 (Figures 6 and 38) pivotally mounted, as at 353, on a projection 352 fixed to the lower edge of the upper cam plate 136.

The other leg of the bell crank 351 has a thrust rod 354 (Figures 24 and 38) pivotally connected thereto which passes through the thrust rod guide bars 175, 176 and, at times, engages the main pattern drum 80 and, at other times, engages a segmental cam 355. When the lower end of the thrust rod 354 is raised by the segmental cam 355, it is apparent that the cam needle raising cam 335 is disposed in engagement with or in close proximity to the needle cylinder 131 to thus engage all of the needle butts and raise all the cylinder needles N as they move thereby (Figure 37).

The needle advancing or raising cam 336 (Figure 6) is engaged by one end of a lever 360 oscillatably mounted intermediate its ends on the upper end of a post 361 whose lower end is fixed in the upper cam plate 136. The rear end of lever 360 is engaged by a bunter 362 in the form of an adjustment screw which is threadably embedded in one leg of a bell crank 363 (Figures 3, 4, 6 and 38) oscillatably mounted, as at 364, on a support bracket 365 whose front is fixed to the lower surface of the upper cam plate 136. The other leg of the bell crank 363 has the upper end of a thrust rod 366 pivotally connected thereto which extends downwardly and through the guides 175, 176 (Figures 4, 6, and 19) and whose lower end, at times, engages the main pattern drum 80 and, at other times, engages a stepped segmental cam 367 fixed to said drum 80.

It is thus seen that, as the lower end of the thrust rod 366 is raised by the cam 367, the needle raising cam 336 will be moved into operative position to thus cause the needle butts and needles N passing thereby to be raised by the cam 336.

It will be observed in Figures 19 and 24 that the position of the segmental cams 355, 367 is such that the

needle raising cams 335, 336 will be in operative position during the knitting of a plain fabric, that is, when all of the stitches are knit on the cylinder needles N, and the cams 335 and 336 will be in inoperative position, or the position shown in Figure 37, during the knitting of

5 5 the rib top.

It will be observed in Figures 2, 4, 6 and 37 that there is also provided a stationary cylinder needle lowering and stitch transfer cam 370 having a horizontal portion and 10 two downwardly extending inclined surfaces. The needle lowering cam 370 is fixedly mounted on the upper end of a vertical stem portion 373 fixedly secured to the upper cam plate 136 (Figures 2 and 6). This needle lowering cam 370 is provided to lower any cylinder needles N raised 15 by the selector jack raising cam 260 after the needles pass the point at which the dial stitch transfer operation takes place. The cylinder needles N are lowered by the cam 370 to hold the transferred stitches in the hooks thereof and to pass these needles through the cylinder stitch cams 20 upon the next revolution of the needle cylinder.

A gate 374 is provided in the upper cam plate 136, similar to the gate 191, to facilitate removal of the selector jacks 116 in the event a butt should become broken or it becomes necessary to change one or more of the 25 selector jacks.

The needle raising switch cam 375 and a needle lowering switch cam 376 are shown in Figure 37 which are conventional in all men's half hose knitting machines and which serve to switch part of the needles up out of action during 30 knitting of the heel and toe and to switch part of the raised needles back into action after knitting the heel and toe.

These switch cams 375, 376 have a novel means of operation in this instance, and, therefore, a description 35 of the means for operating these cams will now be described. The radially movable switch cams 375, 376 are slidably mounted in a cam block 377 (Figures 1, 2 and 6) fixed to the upper cam plate 136. The needle raising cam 375 has a downwardly extending abutment 40 380 secured to the outer end thereof and which is urged outwardly by a spring 381 mounted in a bore in the cam block 377 (Figure 6). The amount of inward travel of the cam 375 may be adjustably limited by an adjustment screw 383 which threadably penetrates the abutment 380 and is locked in position by a lock nut 384.

The outer end of the inclined cam 375 is engaged by the upper leg of a bell crank 386 (Figures 1 and 2) which is oscillatably mounted, as at 387, on an angle clip 390 fixed to the lower surface of the upper cam plate 136 (Figure 2). The other leg of the bell crank 386 has pivotally secured thereto, as at 391, the upper end of an adjustable connecting rod 392 whose lower end is oscillatably connected to a rearwardly extending lever arm 395 (Figures 1 and 3). The lever arm 395 extends rearwardly in Figures 1 and 3 and is oscillatably mounted adjacent its rear end on a stub shaft 396 fixed in the frame 14. The lever arm 395 is adapted to engage cams, not shown, on the auxiliary pattern drum 33 to, at times, cause the connecting rod 392 to move downwardly and thus move the bell crank 386 in a counter-clockwise direction in Figure 2 to move the inclined needle raising switch cam 375 inwardly towards the needle cylinder.

The switch cams 375 and 376 are shown in this application as being used to make a heel similar to the heel structure shown and fully described in a patent to E. A. Hirner, No. 1,154,116, and dated September 21, 1915, but it is to be understood that a conventional heel could be made without affecting the principles of this invention. In making the "Hirner" heel on this machine, there are three lengths butts used on the cylinder needles N, i. e. long, short and medium butt needles. The needle raising cam 375 is limited as to its inward movement by a spacer 415 (Figures 2 and 6) which is, 65 at times, moved into position between the cam block

377 and the adjustable bunter 383 to limit inward movement of the needle raising cam 375.

The spacer 415 is secured to the upper end of a control rod 416, extending downwardly, in Figures 2 and 6, and guided in a guide plate 417. The lower end of the control rod 416 is pivotally connected to the outer end of an operating lever 418 (Figure 1) similar to lever 395, the medial portion of which is adapted to, at times, be engaged by segmental cams, not shown, on the auxiliary pattern drum 33 and to thus lower the spacer 415 and allow the needle raising cam 375 to be moved to fully operative position.

It might be stated that, the inclined needle lowering cam 376 is, at times, moved into operative position or inwardly radially far enough to only lower the long butt needles raised by the cam 375 so they remain down and pass under the cam 304 (Figure 37) through the stitch cams to form stitches thereon and at other times, to be moved to fully operative position to lower all the needles raised by the needle raising cam 375.

The needle lowering switch cam 376 is resiliently urged outwardly by a compression spring 400 (Figure 6) mounted in a bore in the cam block 377. The outer end of cam 376 has a downwardly extending portion 402 thereon which is engaged by the upper end of a bell crank 405 (Figures 2 and 5) which is pivotally mounted, as at 406, on an angle clip 407 fixed to the lower surface of the upper cam plate 136. The inner end of the bell crank 405 has pivotally connected thereto the upper end of an adjustable connecting rod or bar 410 whose lower end is pivotally connected to the outer end of a lever arm 411 (Figure 1) also similar to operating lever 395, which extends rearwardly in Figures 1 and 3 and is pivotally mounted on the stub shaft 396. The auxiliary pattern drum 33 is also provided with stepped cams, not shown, for operating the lever arm 411 in a conventional manner to cooperate with the needle lowering switch cam 375 during knitting of the heel and toe.

Latch ring and yarn feeding mechanism

The novel latch ring and yarn feeding mechanism are best shown in Figures 1, 2, 3, 4, 9, 10, 11, 13 and 14. The latch ring 425 is fixed in a latch ring holder 426 (Figures 2, 4, 9, 10 and 11) as by screws 427. The latch ring holder 426 is secured at one side to a pivot arm 430, as by screws 431 (Figure 10). The pivot arm 430 is pivoted on a shaft 432 fixed in the bifurcated upper end of a latch ring support post 433 fixed on the upper cam plate 136 as by screws 434 (Figures 2, 6 and 12). Diametrically opposite the latch ring support post 433 is another latch ring support post 435 (Figures 2, 6 and 7), which is hollow in cross-section and has an L-shaped block 436 fixedly secured to the upper end thereof and in the upwardly extending bifurcated leg of which a projection 437 is adjustably secured.

The projection 437 is integral with the latch ring holder 426 and has a plate 440 fixed thereon which is adapted to, at times, be engaged by a latching member 441 to lock the latch ring holder 426 in operative position. The latch 441 is pivotally mounted on the L-shaped bracket 436, as at 442, and has an outwardly and downwardly extending tail portion 443 which is resiliently urged in a counterclockwise direction in Figure 2 by a tension spring 444, one end of which is secured to the tail 443 and the opposite end of which is secured to the L-shaped block 436.

It is thus seen that, in the event that an operator wants to inspect the work being knit or if, for any reason, it is necessary to raise the latch ring the operator merely depresses the tail 443 of the latch 441 and raises the latch ring 425. The rear portion of the latch ring 425 has an opening 450 formed therein (Figures 9, 13 and 14) for the reception of a novel form of yarn feeding finger 451 having a yarn passageway 452 therein for the strand of yarn Y. The latch ring holder 426 has

5 a cast yarn feeding finger guide bracket 453 secured thereto, as by screws 454 (Figure 9), in which the yarn feeding finger 451 has vertical sliding movement and which is confined by a plate 455 suitably secured to the casting 453, as by screws 456 (Figures 9, 13 and 14).

The upper end of the yarn feeding finger 451 has a horizontal bar 457 secured thereto which extends beyond the upper end of the yarn feeding finger 451 in Figure 13 and has an adjustment screw 460 therein which serves to limit downward movement of the yarn feeding finger 451. The yarn feeding finger 451 is normally urged upwardly by a tension spring 463 whose lower end is mounted on a screw 464 (Figure 14) and whose upper end is mounted on a shoulder screw 465 mounted in the upper end of the yarn feeding finger 451. The lower end of a connecting link 466 is pivotally mounted on the shoulder screw 465 (Figures 13 and 14). The upper end of the link 466 is pivotally connected, as at 467, to a lever arm 470 oscillatably mounted intermediate its ends, as at 471, adjacent the upper end of an L-shaped support bracket 472.

20 The lower horizontal leg of the bracket 472 is fixed on the latch ring holder 426, as by screws 473 (Figure 9). The outer end of lever 470 is pivotally connected, as at 475, to the upper end of a link 476 whose lower end is pivotally connected, as at 477, to the upper end of a link 480 (Figures 3, 4 and 13). The link 480 extends downwardly and is pivotally connected, as at 481, to the outer 25 end of a crank arm 482 (Figures 3, 4 and 5) pivoted intermediate its ends, as at 483, on a block 484 carried by jack cam plate 12. The other end of the arm 482 is engaged by a clip 485 fixed to a thrust rod 486 (Figures 4 and 5). The thrust rod 486 passes downwardly and is guided in the upper and lower guides 175, 176 and, at times, engages the main pattern drum 30 and, at other times, engages a segmental cam 490 (Figure 23) fixed on the main pattern drum 30.

30 It is thus seen that, when the lower end of the thrust rod 486 is in engagement with the main pattern drum 30, the yarn feeding finger 451 is lowered by the tension spring 463 (Figure 14) to operative position so the yarn will be fed into the hooks of the cylinder needles N and over the dial needles D shown in Figure 14.

Dial and driving means therefor

35 The dial mechanism is generally constructed in a conventional manner although it embodies novel features including the configuration of the dial and novel dial cams 50 for controlling latch-type dial needles during knitting therewith and during the transfer of stitches from dial needles to cylinder needles.

The driving means for the dial may be conventional for 40 rotating and reciprocating the dial in unison with the needle cylinder 131 and jack cylinder 115. The driving means for the dial includes a bevel gear 500 (Figure 1) fixed to the bevel gear 17 and which is engaged by a bevel gear 501 fixed on the lower end of a vertically disposed driving shaft 502 which passes through the hollow columns 137 and 435 (Figures 5 and 7) and extends upwardly and has a bevel gear 504 (Figures 1, 2 and 13) fixed on the upper end thereof which meshes with a bevel gear 505. The bevel gear 505 is fixed on one end of a shaft 506 which is rotatably mounted in a support bracket 507 the 45 lower end of which is fixed, as by screws 508, to the latch ring holder 426 (Figure 13). The inner end of the shaft 506 has a bevel gear 510 fixed thereon (Figures 1 and 2) which meshes with a bevel gear 511 fixedly mounted on a vertically disposed shaft 513 mounted for rotation in a horizontal or arcuate portion of the bracket 507.

50 The lower end of shaft 513 has a dial 514 fixed thereon (Figures 10, 11 and 30 to 34 inclusive) which has radially extending spaced slots therein for the reception of dial needles D. The arcuate portion of bracket 507 has formed integral therewith a downwardly extending sleeve

520 in which the shaft 513 is rotatably mounted and to which a circular cam plate 521 (Figure 10) is suitably secured, as by a set screw 522. The cam plate 521 is adapted to support improved dial cams to be presently described.

Referring to Figures 27, 28 and 29, it will be observed that the dial cams include a stationary irregularly-shaped outer dial cam broadly designated at 525, which may be formed in segments, and stationary inner dial cams 526, 527 each of which is fixed to the lower surface of the cam plate 521. The movable dial cams include a knitting dial cam or dial needle stitch cam 530 which is pivotally secured to the lower surface of the dial cam plate 521, as at 531, and has a passageway 532 formed therein through which the butts of the dial needle D are adapted to pass. The free end of the knitting dial cam 530 has a stud 534 threadably secured therein which passes upwardly through an arcuate slot 535 (Figure 9) in the dial cam plate 521 and penetrates an opening or slot 540 in one end of a lever 542 pivoted, as at 543, intermediate its ends on the inner end of a bracket 544.

The outer end of the bracket 544 is fixed to the latch ring holder 426, as by screws 545 (Figure 9) and the outer free end of the lever 542 has a control wire 546 connected thereto which is shielded in a flexible casing 547. The casing 547 is held against the upper surface of the latch ring holding bracket 426, as by a clip 550 suitably secured to the latch ring holder 426, as by a screw 551. The casing 547 and the control wire 546 extend rearwardly and downwardly in Figures 3 and 4 and their lower ends are fixed in an L-shaped bracket 555 (Figures 3, 4 and 5) which extends forwardly and is suitably secured to the framework 15, as by screws 556 (Figures 3 and 4).

The control wire 546 then extends downwardly and is connected to the outer or rear end of a control lever 558 (Figure 18) oscillatably mounted on the shaft 91 and the reading end of which is adapted to, at times, engage the main pattern drum 80 and, at other times, to engage a segmental cam 560 fixed on the main pattern drum 80. The lever 558 is urged against the pattern drum 80 by a tension spring 561 whose lower end is connected to the rear portion of the lever 558 and the upper end of which is connected to the L-shaped bracket 555.

It is thus seen that, as the reading end of lever arm 558 is engaged by the segmental cam 560, the control cable 546 is moved downwardly in Figure 18 to move the lever 542 shown in Figure 9 in a clockwise direction. This moves the pin 534, in the slot 535, and moves the dial needle stitch cam 530 from the position shown in Figure 29 to substantially the position shown in Figure 27. As the dial 514 is rotated to move the butts on the dial needle D along the pathway 532 in the dial stitch cam 530 it is apparent that the dial needles D will then move outwardly to take the yarn Y in the hooks thereof as they pass beneath the yarn feeding finger 451 in the position shown in Figure 14.

The other movable cams carried by the dial cam support plate 521 include dial needle pushout cam or transfer cam 570 (Figures 27, 28 and 29) in which a trackway 571 is cut for the reception of the butts of the dial needles D. The pushout cam 570 is the primary of a pair of co-acting dial transfer cams, the secondary of which will be later described.

The dial needle push-out cam 570 is pivotally mounted, as at 575, beneath the dial cam plate 521 and is provided with a stud 576 which extends upwardly through an opening 580 in the dial cam supporting plate 521 (Figure 9). The stud 576 is, at times, engaged by one end of a control arm 581 which extends forwardly in Figure 9 and is pivotally mounted, as at 582, on the latch ring supporting bracket 426.

The inner end of the arm 581 has one end of a flexible control wire 583 connected thereto which extends to the left in Figure 9 and enters a control wire casing 584. One end of the casing 584 is fixed to the latch ring sup-

porting bracket 426, as by a clip 585 held thereon by a screw 586. The casing 584 and the wire 583 extend rearwardly and downwardly and the lower end of the casing 584 is fixed in the rear end of an arm 587 (Figures 1, 4 and 7) whose front end is suitably secured to the pillar or column 433 (Figure 4), as by screws 588.

The control cable 583 then extends downwardly and is connected to one end of a lateral control lever 590 (Figures 4, 5 and 38) which is oscillatably mounted intermediate its ends, as at 591, on an angle clip 592. The inner end of the control arm 590 is engaged by a bunter 593 fixed to the upper end of a thrust rod 594. The thrust rod 594 extends downwardly through the upper and lower thrust rod guides 175, 176 and is adapted to, at times, engage the main pattern drum 80 and, at other times, to engage a segmental cam 595 fixed on the main pattern drum 80 (Figure 20).

The primary dial needle push-out or transfer cam 570 is urged inwardly to the position shown in Figures 9 and 29 by a tension spring 596 (Figure 9) one end of which is connected to the dial cam supporting plate 521 and the other end of which is connected to a spring anchor 597 suitably secured to the stud 576 extending upwardly through the opening 580 in the dial cam supporting plate 521.

It is thus seen that, when the thrust rod 594 (Figure 20) is resting on the main pattern drum 80, the dial needle pushout cam 570 occupies the position shown in Figures 9 and 29 and upon the thrust rod 594 being raised by the segmental cam 595, the control wire 583 will be pulled, or moved from right to left in Figure 9, to thus move the control arm 581 in a counterclockwise direction, pivoting the dial needle push-out cam 570 about its pivot point 575 from the position shown in Figures 9 and 29 to the position shown in Figures 27 and 28.

The primary dial needle push-out cam 570 is also provided with an overhanging portion 598 (Figures 27, 28, 29 and 33) in which a portion of a secondary dial needle transfer cam 600 is slidably mounted. The secondary dial needle transfer cam 600 is slotted, as at 601 (Figure 33), and is held in sliding engagement with the overhanging portion 598 of the primary dial needle push-out cam 570 by a pair of shoulder screws 602 passing through the slot 601 in the secondary dial needle transfer cam 600 and being threadably embedded in the overhanging portion 598 of the dial needle push-out cam 570. The overhanging portion 598 of the dial push-out cam 570 is also provided with a slot 603 for the reception of a stud 604 whose lower end is fixed in the secondary dial needle transfer cam 600 and whose upper portion extends through the slot 580 in the dial cam supporting plate 521 (Figures 9 and 28).

As the primary dial needle push-out cam 570 is moved outwardly from the position shown in Figure 29 to the position shown in Figure 27, in the manner previously described, the secondary dial needle transfer cam 600 is also moved to the position shown in Figure 27 so that the butts of the dial needles D are not pushed outwardly radially any further than they are ordinarily pushed outwardly by the groove 571 in the dial needle push-out cam 570. However, at the time of transfer, the secondary transfer dial needle cam 600 is caused to move outwardly further, to the position shown in Figure 28, by one end of a bell crank 605 (Figure 9) engaging and moving the stud 604 so the dial needle transfer cam 600 then occupies the position shown in Figure 28.

Thus, the primary dial needle push-out cam 570 moves the dial needles D partially outwardly to prepare the loops thereon for the transfer operation by stretching the loops so the corresponding cylinder needles N can pass upwardly therethrough. This will be more clearly explained later in this context. Of course, the secondary dial transfer cam serves to subsequently move the dial needles D fully outward to where their latches pass through the loops so the outer cam 525 will subsequently

withdraw the dial needles D from the loops as they remain impaled on corresponding cylinder needles N.

The bell crank 605 (Figure 9) is oscillatably mounted, as at 606, on the dial cam supporting plate 521 and has one end of a control wire 607 fixed thereto which extends rearwardly therefrom and through a control wire casing 610. One end of casing 610 is fixed to the latch ring holder or support bracket 426, as by a plate 611 and screw 612. The control wire 607 and its casing 610 extend rearwardly and downwardly in Figures 4 and 9 and the lower end of the casing 610 is fixed in the bracket 555. The control cable 607 extends below the casing 610 and its lower end is connected to the outer end of a control lever 613 (Figure 3), the medial portion of which is oscillatably mounted on the shaft 91 and the reading end of which, at times, engages the main pattern drum 80 and, at other times, engages a segmental cam 614 fixed thereon. The crank lever 613 is urged into engagement with the main pattern drum 80 by a tension spring 615 (Figure 3).

It is thus seen that, upon the segmental cam 614 engaging the reading end of lever 613, the control wire 607 will be pulled downwardly in Figure 3 and rearwardly in Figure 9 to thus move the bell crank 605 in a counterclockwise direction and to move the secondary dial needle transfer cam 600 from the position shown in Figure 27 to the position shown in Figure 28. The bell crank 605 is urged in a counterclockwise direction by a tension spring 616 (Figure 9) one end of which is secured to the bell crank 605 and the outer end of which is secured to a spring anchor 617 secured in the hub of the dial cam supporting plate 521.

An arcuate dial needle latch intercepting element or supporting plate 620 (Figures 9, 27, 28, 29, 32 and 33) is disposed radially outward of the transfers cams 570, 600 and has an inwardly extending horizontal tail portion 621 (Figure 9) integral therewith which is fixed to the dial cam supporting plate 521, as by a screw 622 (Figures 9 and 33).

The dial needle latch intercepting plate 620 is provided to intercept and prevent the latches of the dial needles D from laying backwards or to support the latches in substantially vertical position, as shown in Figure 32, when the dial needles D are moved outwardly in the trackway 571 in the dial needle push-out cam 570 after the dial needle push-cut cam 570 has been moved from the position shown in Figures 9 and 29 to the position shown in Figures 27 and 28.

This movement of the dial needle push-out cam 570 is effected immediately preceding the transfer operation, that is, when the stitches which have previously been knit by dial needles are transferred to the cylinder needles. The latches of the dial needles D are supported in this position (Figure 32) so the stitches held in the hook of the dial needles D may not pass over the latch to be shed until after the corresponding cylinder needles N have been raised upwardly through the stitches to the position shown in Figure 32. Immediately after cylinder needles N have passed through the dial stitches, the secondary dial needle transfer cam 600 is moved to the position shown in Figure 28 to further advance the dial needles D outwardly radially of the dial to substantially the position shown in Figure 33 where the loop formed over the corresponding dial needle D may then pass inwardly and over the latch of the dial needle D. As the dial needle D is then drawn in again by the stationary outer dial cam 525 the latch of the dial needle D is caused to close by the loop around the stem portion thereof moving over the same to thus shed the stitch from the dial needle D onto the cylinder needle N to complete the transfer operation from the dial needle D to the cylinder needle N.

It should be noted that the dial 514 has a relatively thin peripheral portion 514a (Figure 10) whose outer edge terminates inwardly of and closely adjacent the circular path of travel of the cylinder needles N for pressing the

stitches off the dial needles during the drawing of stitches and during the transfer operation. This thin portion 514a overlies the nibs of the sinkers 142 with space between said nibs and the dial portion 514a sufficient only for the fabric to pass therebetween as it is knit. Thus, the nibs of the sinkers hold the dial stitches inward against the dial 514 with sufficient tension to permit the dial needles to withdraw from the stitches at the dial transfer and dial knitting stations. This obviates the necessity of providing take-up or tension means for the fabric and thereby eliminates the separating of successively knit fabrics and the consequent removal of pull-threads. This also eliminates the need for expensive saw-tooth sinkers such as have had to be used heretofore in order to knit separate fabrics continuously.

Latch opener and yarn cutting and clamping means

The dial cam supporting plate 521 and the stationary outer dial cam 525 are cut to form an opening 630 therein (Figures 9, 27, 29 and 30) for the reception of an inclined lower pointed portion 631 of a latch opener 632. The latch opener 632 extends upwardly through the dial cam 525 and the dial cam supporting plate 521 and is slidably mounted in a guide block 633 (Figures 9 and 10) fixed on an L-shaped bracket 634 the foot portion of which is fixedly secured to the dial cam support plate 521 as by screws 635. The latch opener 632 is resiliently urged downwardly by a tension spring 636 (Figures 9 and 11) the lower end of which is secured to the L-shaped bracket 634 and the upper end of which is connected to a screw 637 threadably embedded in a collar 640 and which serves to adjustably secure the collar 640 to the upper end of the latch opener 632.

The lower surface of the collar 632 engages the bifurcated end of a bell crank 641 oscillatably mounted, as at 642, on the upper end of an L-shaped bracket 643. The lower horizontal foot portion of bracket 643 is fixedly secured to the dial cam support plate 521, as by screws 644. The bell crank 641 is controlled by a control wire

650, one end of which is connected to the bell crank 541 and which extends rearwardly in Figure 9 and through a flexible casing 651. One end of casing 651 is fixedly secured to the yarn feeding finger bracket 453 as by a block 652.

45 The casing 651 and the control cable 650 extend rearwardly and downwardly in Figures 3 and 6 and the lower end of the casing 651 is secured to a support bracket 655 (Figures 3, 6, and 38) extending inwardly and being fixedly secured on the upper cam plate 136. The control wire 650 extends downwardly therefrom (Figure 3) and its lower end is connected to the upper end of a thrust rod 657. The thrust rod 657 extends downwardly through the upper and lower thrust rod guides 175 and 176 and is adapted to, at times (Figures 25 and 38), engage the main pattern drum 80 and at other times, engage and be raised by a segmental cam 660 fixedly secured thereto.

It is thus seen, that as the segmental cam 660 raises the thrust rod 657 the control wire 650 will allow the tension spring 636 (Figure 11) to move the latch opener 632 downwardly through the guide block 633 to substantially the position shown in Figure 30. It will be noted in Figures 29 and 30 that the pointed end of the lower portion of the latch opener 631 is then positioned inwardly of and on the level of the hooks of the dial needles, and the lower portion of the latch opener extends inwardly at an angle to the path of travel of the dial needles as well as upwardly at a slight angle so the inclined pointed portion 631 of the latch opener 632 will then engage and open the latches of the dial needles D so the latches will be open when the dial needles D pass beneath the yarn feeding finger 451 for taking the yarn Y in the hooks thereof substantially as shown in Figure 14. A spring 658 urges thrust rod 657 against cam 660 and pattern drum 80 (Figure 25).

70 Tapered latch actuating grooves 663 and 664 (Figure

27) are provided in the stationary cam 525 subsequent to the knitting and transfer stations respectively. The groove 663 is provided to completely close any latches not closed by the stitches being shed from the dial needles D and the groove 664 is provided to completely open any latches which may be partially opened by the loops of yarn in the hooks thereof at the transfer station.

Upon completion of a sock or other knit article, the yarn feed finger 451 is withdrawn or raised in Figure 14 to inoperative position relative to the cylinder and dial needles to thus cause the yarn Y to pass partially over the dial cam support plate 521 and beneath a yarn holding finger or leaf spring yarn clamp 665 (Figure 9) fixedly secured to support plate 521, as by a screw 666. The yarn Y then passes between a pair of open scissor type blades 670, 671 (Figures 9 and 10) which are mounted on a block 672 fixed on the dial cam supporting plate 521. The movable blade 671 is oscillatably mounted on a shoulder screw 675, intermediate its ends, and has the lower end of a rod or link 676 (Figures 9 and 10) pivotally connected thereto whose upper end is fixedly secured in a control lever 677 which extends rearwardly in Figure 9 and is oscillatably mounted intermediate its ends, as at 680 (Figures 2, 9 and 13) on the bracket 472.

The outer end of lever 677 is pivotally mounted, as at 681, on the upper end of a connecting arm 682 and the lower end of arm 682 is pivotally connected to the outer end of a crank arm 683 (Figures 2, 4 and 5) the medial portion of which is oscillatably secured to the bracket 484. The inner end of the crank arm 683 is adapted to be engaged by a bunter 684 fixedly secured to the upper end of a thrust rod 685. The thrust rod 685 extends downwardly through the thrust rod guides 175 and 176 and its lower end (Figure 22), at times, engages the main pattern drum 80 and, at other times, engages a segmental cam 686 fixedly secured to the main pattern drum 80.

It is thus seen that, as the lower end of the thrust rod 685 is raised by the segmental cam 686 the blade 671 will move away from the blade 670 to thus form a scissor opening between the blades and, after the yarn Y is passed therebetween in the manner previously described, the main pattern drum 80 will then move another step in rotation to allow the lower end of the thrust rod 685 to drop downwardly off the cam 686 to thus quickly close the blades 670 and 671 and sever the yarn Y therefrom. The yarn loops remaining on the cylinder needles N are then pressed off the hooks thereof by passing the cylinder needles N through the conventional stitch cams without feeding a yarn Y thereto.

Method of operation

After each successive sock or other knitted article is knit, the yarn feeding finger 451 returns to lowered or operative position as best shown in Figures 13 and 14. At this time, the needle raising cams 335, 336 and the cams 375, 376 occupy inoperative positions as shown in Figure 37 and the movable cams in the dial mechanism occupy the inoperative or withdrawn positions shown in Figure 29. Of course, as the yarn feed finger 451 returns to operative position, or immediately preceding movement of the yarn feed finger 451 to operative position, the knitting cam 530 is swung outwardly to operative position as shown in Figures 12 and 27, although the transfer cams 570, 600 remain in the inoperative position shown in Figure 29. Also, at some time before the yarn feed finger 451 moves to operative position, the pointed portion 631 of the latch opener 632 moves into operative position as best shown in Figures 29 and 30.

In this instance, the machine is shown as being provided with twenty dial needles D and sixty cylinder needles N with sixty selector jacks 116 corresponding to the sixty needles N. Also, the pattern butts in Figure 16 are particularly arranged for knitting a one-by-two rib fabric. However, it is to be distinctly understood that the arrange-

ment of the pattern butts may be varied to vary the character of the rib fabric knitted on this machine, the number of cylinder needles N may be varied relative to the number of dial needles D and a greater or lesser number of dial needles and cylinder needles may be employed, if desired.

At substantially the time the yarn feed finger 451 returns to operative position, the two selector fingers 201, 202 (Figure 37) of the primary or first set move into operative position while the remaining selector fingers 200, 203, 280, 281 remain in withdrawn or inoperative position. Thus, as the selector jacks 116 and needles N move from right to left in Figure 37, the butts b and c thereon (Figure 16) engage the respective selector fingers 201, 202 to elevate the corresponding jacks, which are every third jack in this instance, so the master butts 194 on the latter jacks engage and ride up the jack advancing cam 193 while the butts 194 on the intervening jacks 116 continue to move in a straight line beneath the jack advancing cam 193. It follows that every third jack and its corresponding needle N is raised so these needles pass above the stitch cam 302 to take the yarn Y in the hooks thereof.

At the same time, all of the dial needles D are moved 25 outwardly by the dial stitch cam or knitting cam 530 to also take the yarn Y in the hooks thereof (Figures 14 and 31), after which the dial needles D are withdrawn by the stationary outer dial cam 525 as the cylinder needles N are lowered by the stitch cam 303. Thus, the 30 make-up course is formed as the yarn is fed to twenty cylinder needles and twenty dial needles, in this instance.

After the make-up course is formed, the remaining 35 two selector fingers 200, 203 (Figure 37) in the primary set are moved into operative position so that all of the 40 butts in the rows a, b, c, d on the corresponding jacks 116 engage the respective selector fingers 200, 201, 202, 203 to cause the butts 194 on spaced pairs of jacks 116, separated by a single intervening jack 116, to engage and ride up the jack advancing cam 193 and to thereby elevate 45 the corresponding needles N to take the yarn in the hooks thereof and to subsequently form stitches therefrom. The jacks 116 whose butts 194 are not elevated by the jack advancing cam 193 continue to move in a straight line from right to left in Figure 37 so the butts of the needles N thereabove pass beneath the stitch cams, these particular needles being those which correspond to the dial needles D. Thus, successive courses are formed in this 50 manner wherein it is apparent that the yarn Y is fed to, and knit by, forty cylinder needles N and twenty dial needles D to produce a one-by-two rib fabric in which spaced pairs of cylinder needles N form outwardly facing stitches and every third stitch, formed by the dial needles D interposed between adjacent pairs of active cylinder needles, is formed as an inwardly facing stitch.

55 Any desired number of courses may be knit in the manner described, such as in producing a ribbed top for a sock or other article, whereupon stitches may be transferred from the dial needles D to said intervening cylinder needles N by first moving the primary transfer cam or 60 dial needle push-out cam 570 outwardly to operative position, from the position shown in Figure 29 to the position shown in Figure 27.

The primary dial transfer cam or dial needle push-out cam 570 may be moved outwardly to operative position a substantial number of courses in advance of the movement of the secondary dial needle transfer cam 600, if desired, without affecting normal operation of the dial needles and cylinder needles in the manner heretofore described.

70 As a matter of fact, the primary dial needle transfer cam or push-out cam 570 could remain in fully operative position at all times if it were not for the fact that the needles must rotate, at times, in a reverse or clockwise direction in Figures 27 and 29 during reciprocatory knitting of the heel pocket and toe of a sock. By referring

to Figure 27, it is apparent that movement of the dial needles in a clockwise direction would be impeded by the butts thereof engaging projections on the primary transfer cam 570 defining the race or groove 571 therein, or the butts on the cylinder needles might even be broken away, if the primary transfer cam or dial push-out cam 570 remained in operative position during clockwise rotation of the dial needles D and cylinder needles N.

As the primary dial needle transfer cam or push-out cam 570 is swung to operative position (Figure 27) from the position shown in Figure 29, it is apparent that the dial push-out cam 570 initially moves relative to the secondary dial needle transfer cam 600 and then moves the secondary dial needle transfer cam 600 outwardly therewith to partially operative or intermediate position.

Thus, the dial needles D are moved outwardly in advance of the transfer point by the primary dial transfer cam or push-out cam 570, and relative to the stitches thereon, causing the latches to swing upwardly, at which time the movement of the latches is intercepted by the latch intercepting element or plate 620 thereby holding the stitches on the dial needles open (Figure 32), preparatory to passage of the corresponding cylinder needles N upwardly therethrough as shown in Figure 32.

However, the cylinder needles N corresponding to the dial needles D are not moved upwardly through the stitches carried by the dial needles until the secondary dial needle transfer cam 600 is moved from the position shown in Figure 27 to the fully operative or outward position shown in Figure 28, by the bell crank 605 in the manner heretofore described. Thus, if the dial needles D are moved outwardly by dial transfer cam 570 and the secondary dial transfer cam 600 is not in fully operative position and the cylinder needles N are not raised to pass through the stitches carried by the dial needles, it is apparent that, as the dial needles D move out of the radial plane of the dial needle latch intercepting element 620, the latches on the dial needles D may then swing inwardly to lay upon the shanks of the dial needles D as the dial needles D are subsequently withdrawn by the stationary outer dial cam 525.

During the transfer operation, the secondary dial transfer cam 600 is moved outwardly relative to the primary dial transfer cam or push-out cam 570 from the position of Figure 27 to that of Figure 28 and the selector fingers 280, 281 in the secondary set are moved inwardly to operative position.

Since the selector fingers 280, 281 are disposed on a lower level than the first set of fingers 200—203 and, since the leveling butts 198 on any of the selector jacks 116 elevated by selector fingers 200—203 engage the leveling cam 197 to return the corresponding jacks to their lowermost positions, the rows of lower pattern butts e, f successively engage the selector fingers 280, 281, respectively, so those selector jacks 116 corresponding to the dial needles D are elevated to where the butts 194 thereon will engage and ride up the secondary jack advancing cam 260 (Figure 37).

It should be noted that this will cause the butts of the needles N to move upwardly beneath the horizontal portion of the stationary needle cam 370 while causing the hooks of these needles to move to substantially the position shown in Figure 32. Since the dial needles D are moved outwardly by the primary dial needle transfer cam 570 and the latches thereon are intercepted by the arcuate plate 620, the stitches on successive dial needles D are held open to permit the corresponding needles N to pass upwardly therethrough, as shown in Figure 32, so the stitches on the dial needles D are also disposed between the hooks and latches of the corresponding cylinder needles N. Immediately thereafter, while the cylinder needles N are still in elevated position at the transfer point, the butts of the dial needles D engage and are further projected outwardly by the secondary dial needle transfer cam 600, thereby moving the latches on the dial

needles through the corresponding stitches thereon as shown in Figure 33.

It should be noted that the secondary dial transfer cam 600 moves the dial needles outward sufficiently to permit the latches thereon to lay back against the shanks of the dial needles so that, as the dial needles are again withdrawn by the stationary outer dial cam 525, the latches are closed by the stitches as the dial needles D are withdrawn therefrom so the stitches previously held by the dial needles D are then held only by the corresponding cylinder needles N.

Thereafter, the cylinder needles to which the dial stitches have been transferred, are lowered by the cylinder needle cam 370 so that all the stitches in the corresponding course are then held in the hooks of the cylinder needles only. At this time, all of the movable dial cams are returned to the inoperative position shown in Figure 29, all of the selector fingers 200, 201, 202, 203, 280 and 281 are withdrawn to inoperative position and the needle raising cams 335, 336 are moved inwardly to operative position whereupon conventional knitting then takes place. All of the selector jacks 116 will then remain in lowered position and move in a straight line throughout each revolution of the needle cylinder and the needles N will be successively elevated by the cams 335 and 302 for taking the yarn Y in the hooks thereof in the usual manner, after which the needles N are lowered by the stitch cam 303 to form stitches therewith.

Any desired number of courses may be knit in this manner after which the heel, foot and toe of the sock are knit in a conventional manner.

In knitting the heel and toe the number of needles in action are decreased in some courses by the narrowing picks 310, 311 and the number of needles in action are increased in other courses by the widening pick 316 as the needles reciprocate thereby.

It should be noted that the right-hand portion of the stationary needle cam 370 is inclined in order to insure that the butts of the needles N, when moving from right to left in Figure 37, will not pass beneath or engage the end of the stationary needle cam 370. The needle cams 375, 376 function in the usual manner for separating long-butt needles from short-butt needles preparatory to the widening and narrowing of the fabric in the heel and toe of the sock and a detailed description of their operation is thus deemed unnecessary. Upon completion of each successive sock or other article, the yarn feeding finger 451 is again raised to inoperative position and the yarn Y is cut and clamped in the manner heretofore described, whereupon the stitches are shed from the cylinder needles N as the needles are lowered by the stitch cams without yarn being fed thereto.

During reciprocatory knitting, it is necessary that the pointed portion 631 of the latch opener 632 be raised to inoperative position in order to insure that the pointed portion 631 of the latch opener 632 is not damaged and will not exert undue pressure on the dial needles D. However, the latch opener 632 is a necessary and important feature of the present invention since this constitutes the only means by which the latches of the dial needles D are opened during the knitting of the ribbed top. Of course, it is necessary that these latches be fully opened for taking the yarn Y in the hooks thereof in the forming of the make-up course of a subsequent sock in the manner heretofore described.

The latch opener 632 also insures that any latches which may have been thrown outwardly as the dial needles were previously withdrawn following outward movement thereof, as effected by the primary dial needle transfer cam 570, will be opened prior to being moved outwardly by the dial knitting cam 530 and prior to movement of the secondary dial needle transfer cam 600 to fully operative position or from the position shown in Figure 27 to that shown in Figure 28. Of course, when the secondary dial needle transfer cam 600 is moved to fully operative posi-

tion shown in Figure 28, the dial needle stitch cam or knitting cam 530 is substantially simultaneously swung inwardly to inoperative position to insure that the dial needles from which the stitches have been transferred to corresponding cylinder needles N will not again take the yarn Y in the hooks thereof.

It is well known that it is desirable to vary the length of the stitches formed from time to time, particularly in the forming of the loopers rounds and, since the relatively large jack cylinder 115 is provided in order to facilitate the production of highly varied pattern effects or to facilitate providing jacks of substantial lengths so that a substantially large number of pattern butts may be provided thereon, the relatively short needle cylinder 131 is also an extremely important feature of the present invention, since it may be easily raised and lowered in the manner heretofore described without placing the various operating parts of the machine under undue stress.

Also, since the needle cylinder 131 is raised and lowered independently of the selector jack cylinder 115, this insures that the butts on the selector jacks 116 are always properly aligned relative to the selector fingers 200—203, 230 and 281.

The gates 191, 374 in Figure 37 are provided to facilitate replacing any selector jacks 116 which may have become damaged or worn and it will be observed in Figures 9 and 27 that the stationary outer dial cam 525 is also provided with a removable gate 699 therein to facilitate replacement of any dial needles D which may become damaged or worn.

In the drawings and specification there has been set forth a preferred embodiment of the invention and, although specific terms are employed they are used in a generic and descriptive sense only and not for purposes of limitation, the scope of the invention being defined in the claims.

I claim:

1. In a circular knitting machine, a cylinder, a dial, a set of latch needles on the dial, a set of latch needles on the cylinder; the combination of stitch transferring means comprising means to move each successive dial needle outward to an intermediate position from inward position to cause the stitch thereon to partially open the corresponding latch, stationary dial latch intercepting means against which the latch thus opened is moved to restrict opening of said latch, means to move the hook of the corresponding cylinder needle through the last-named stitch, means to again move the dial needle outward to fully extended position so the latch thereon is moved beyond and released from the intercepting means, and means operable thereafter for withdrawing each successive dial needle from the corresponding stitch transferred to the adjacent cylinder needle.

2. In a circular knitting machine having a circular series of vertically movable cylinder latch needles, a dial, radially movable dial latch needles and means for knitting some stitches on the dial needles and other stitches on the cylinder needles to form a rib fabric; the combination of means to move the dial needles outwardly whereby the latches on the dial needles are opened by the stitches thereon, means to intercept the latches on the dial needles as they are swung open to cause said latches on the dial needles to extend substantially perpendicular to the shanks of the dial needles and to thereby open the stitches carried by the dial needles, means to raise the cylinder needles corresponding to the dial needles through the stitches carried by the dial needles while said latches on the dial needles are intercepted, means operable thereafter to release the latches on the dial needles from said intercepting means to permit the latches to lay back against the shanks of the dial needles, and means for thereafter withdrawing the dial needles from the stitches whereby said stitches previously held by the dial needles are then held by the cylinder needles.

3. In a circular knitting machine having a circle of in-

dependent vertically movable cylinder latch needles and a dial having independent radially movable dial latch needles; the combination of means for transferring stitches from the dial needles to the corresponding cylinder

5 needles comprising means for moving each successive latch needle outwardly a predetermined distance adjacent the transfer point whereby the stitches on the dial needles cause the latches thereof to open, means disposed in the path of the latches as they are opened 10 to limit the opening movement thereof to where the latches project through the loops on the dial needles to hold said loops open, means to raise the corresponding cylinder needles so the hooks thereof pass upwardly through said open loops carried by the dial needles, 15 means operable thereafter for further moving each successive dial needle outwardly to clear the latches thereon from said limiting means whereby the stitches on the dial needles cause the corresponding latches to lay back against the shanks of the dial needles as the dial needles are moved outwardly and as the latches on the dial needles are moved outwardly beyond the corresponding stitches, means to thereafter withdraw the dial needles 20 from the corresponding stitches whereby said corresponding stitches remain impaled on the corresponding cylinder needles, and means for thereafter lowering the cylinder needles to permit knitting to continue solely with cylinder needles.

4. In a structure according to claim 3, means to open the latches on the dial needles after they are closed 25 due to the latch needles withdrawing from the corresponding stitches.

5. In a circular knitting machine having a circular series of vertically movable independent needles, a dial having a plurality of radially movable independent dial 30 latch needles, there being lesser number of dial needles than there are cylinder needles, a dial knitting station, a cylinder knitting station disposed adjacent the dial knitting station, and means for feeding yarn to the dial and cylinder needles in advance of the respective dial and cylinder knitting stations; the combination of means 35 for transferring stitches from the dial needles to corresponding cylinder needles comprising a normally inoperative radially movable primary dial transfer cam, means for moving the dial transfer cam outwardly to thereby move successive dial needles outwardly a predetermined distance, a relatively short stationary arcuate plate disposed radially of the primary dial transfer cam and spaced above the path of travel of the dial needles as they are moved outwardly whereby the stitches on the dial needles will cause the latches thereon to swing 40 upwardly and engage the arcuate plate, means for raising corresponding cylinder needles through the stitches held open by the latches on the dial needles, means for again moving the dial needles outwardly to where the latches thereof move beyond the arcuate plate and are 45 permitted to move inwardly and downwardly adjacent the shanks of the dial needles and to where the latches on the dial needles are moved outwardly beyond the corresponding stitches, and means to withdraw the needles from the stitches thus transferred to the cylinder needles 50 whereby knitting continues on all of the cylinder needles.

6. In a circular knitting machine having a circular series of vertically movable independent latch needles, a dial having a plurality of radially movable independent dial latch needles, there being lesser number of 55 dial needles than there are cylinder needles, a dial knitting station, a cylinder knitting station disposed adjacent the dial knitting station and means for feeding yarn to the dial and cylinder needles in advance of the respective dial and cylinder knitting stations; the combination of means for transferring stitches from the dial needles to corresponding cylinder needles comprising a normally inoperative radially movable primary dial transfer cam, means for moving the primary transfer cam outwardly to thereby move successive dial needles outwardly a predetermined distance, a relatively short sta-

tionary arcuate plate disposed radially of the primary dial transfer cam and spaced above the path of travel of the dial needles as they are moved outwardly whereby the stitches on the dial needles will cause the latches thereon to swing upwardly and engage the arcuate plate, means for raising corresponding cylinder needles through the stitches held open by the latches on the dial needles, means for again moving the dial needles outwardly to where the latches thereof move beyond the arcuate plate and are permitted to move inwardly and downwardly adjacent the shanks of the dial needles and to where the latches on the dial needles are moved outwardly beyond the corresponding stitches, means to withdraw the dial needles from the stitches thus transferred to cylinder needles whereby knitting continues on all of the cylinder needles, and means for opening the latches on the dial needles which were closed as the dial needles withdrew from said corresponding stitches preparatory to repeating the knitting of fabric wherein some stitches are formed on the dial needles and others are formed on cylinder needles.

7. In a circular knitting machine having a circular series of vertically movable independent cylinder latch needles, a set of cylinder stitch cams, a yarn feeding finger disposed above the stitch cams, a dial, a plurality of circularly spaced radially movable dial latch needles carried by said dial and a selector jack positioned beneath each cylinder needle; the combination of a relatively short needle cylinder in which said cylinder needles are mounted for vertical movement, a selector jack cylinder disposed beneath the needle cylinder, means for raising and lowering the needle cylinder relative to the jack cylinder for varying the lengths of stitches formed by the cylinder needles, means to select certain jacks to cause the latter to be raised for raising corresponding needles to take the yarn in the hooks thereof and to pass through the stitch cams and draw stitches therewith, a transfer mechanism on said dial comprising means spaced from the yarn feeding finger and the cylinder needle stitch cams for projecting the dial needles outwardly whereby the stitches thereon cause the latches thereon to move upwardly, means intercepting movement of the latches on the dial needles to cause the latter to remain in a substantially upright position, second selector means operating upon other of said jacks for raising the same along with others of the cylinder needles to cause the latter needles to move upwardly through the loops held open by the substantially upright latches on the dial needles, means to thereafter again move the dial needles outwardly to where the latches are free of the intercepting means and to thereby permit the latches on the dial needles to be moved outwardly through the corresponding stitches, means for thereafter withdrawing the dial needles from the corresponding stitches to transfer the latter onto the corresponding cylinder needles, and means for thereafter lowering the needles to which the stitches have been transferred to resume plain knitting on cylinder needles only.

8. In a structure according to claim 7, means for opening the latches on the dial needles prior to knitting again being started on both the dial needles and some of the cylinder needles.

9. In a circular knitting machine having a circular series of vertically movable independent cylinder latch needles, a set of cylinder stitch cams, a yarn feeding finger disposed above the stitch cams and a selector jack positioned beneath each cylinder needle; the combination of a relatively short needle cylinder in which said cylinder needles are mounted for vertical movement, a selector jack cylinder disposed beneath the needle cylinder and in which said jacks are mounted for vertical movement, and means for raising and lowering the needle cylinder relative to the jack cylinder for varying the lengths of stitches formed by the cylinder needles.

10. That method of transferring stitches from latch dial needles to latch cylinder needles on a circular knitting machine which comprises moving each successive latch dial needle from withdrawn position to an extended position to cause the stitch thereon to deflect the latch thereon upwardly, holding the latch in substantially upright position to hold the stitch open while raising the hook of an adjacent cylinder needle through the stitch, then releasing the latch on the dial needle while passing the last-named latch through the stitch, and then withdrawing the dial needle from the stitch so it remains impaled on the adjacent cylinder needle.

11. In a circular knitting machine having a rotary needle cylinder, a dial, a set of rotary dial latch needles on the dial movable in unison with the cylinder, a set of latch needles on the cylinder, means for, at times, rotating the needle cylinder and the set of dial needles and means for, at other times, reciprocating the cylinder and the set of dial needles on the dial; the combination of stitch transferring means comprising means to move each successive dial needle outwardly to an intermediate position from inward position to cause the stitch thereon to partially open the corresponding latch, stationary dial latch interrupting means against which the latch thus opened is moved with rotary movement of the needle cylinder and the set of dial needles to restrict opening of said latch, means to move the hook of the corresponding cylinder needle through the last-named stitch, means to again move the latter dial needle outwardly to full extended position so the latch thereon is moved beyond and released from the interrupting means, means operable thereafter for withdrawing each successive dial needle from the corresponding stitch transferred to the adjacent cylinder needle, a latch opener having an inclined portion thereon provided with a pointed free end, the pointed free end of the latch opener, while said latch opener is in operative position, being disposed inwardly of and on the level of the hooks of the dial needles and at a point subsequent to the point at which the dial needles are withdrawn from the corresponding stitch, said inclined portion extending inwardly from the pointed free end thereof at an angle to the path of travel of the dial needles and also upwardly at a slight angle and toward the direction of movement of the dial needles during rotary work, and means to move the inclined portion of the latch opener into operative position for opening the latches on the dial needles during circular rib knitting and for withdrawing the inclined portion at least during reciprocation of the cylinder and the set of dial needles.

12. That method of knitting on a circular knitting machine of the type having latch dial needles and latch cylinder needles which comprises knitting solely with the cylinder needles, shedding all the stitches from the cylinder needles, opening the latches on the dial needles, feeding yarn to and knitting with dial needles and cylinder needles, transferring stitches from dial needles to corresponding cylinder needles by moving each successive dial needle from withdrawn position to an extended position to cause the stitch thereon to deflect the latch thereon upwardly, holding the latch in substantially upright position to hold the stitch open while raising the hook of an adjacent cylinder needle through the stitch, then releasing the latch on the dial needle while passing the last-named latch through the stitch, and then withdrawing the dial needle from the stitch so it remains impaled on the adjacent cylinder needle.
